UNITED STATES PATENT OFFICE.

BENJAMIN FLETCHER, OF TORONTO, CANADA.

CONTINUOUS MOLDING-MACHINE.

SPECIFICATION forming part of Letters Patent No. 690,716, dated January 7, 1902.

Application filed August 23, 1901. Serial No. 72,976. (No model.)

To all whom it may concern:

Be it known that I, BENJAMIN FLETCHER, of the city of Toronto, in the county of York and Province of Ontario, Canada, have invented certain new and useful Improvements in Continuous Molding-Machines; and I do hereby declare that the following is a full, clear, and exact description thereof, reference being had to the accompanying drawings, which form part of this specification.

My invention relates particularly to improvements in a continuous molding-machine partially automatic in action and consisting of an endless chain of molds traveling in a horizontal position and receiving the contents to be molded or formed, "after the fashion of the interior of the molds," from the contents on the table, through the center of which they continually pass, and toward the upper and lower compression-wheels, and finally over the discharging-wheel, where the contents of the molds are continuously discharged into a suitable chute leading to a receptacle.

For convenience the drawings illustrating my invention show in this instance the machine adapted for molding or forming what are commonly known as "popcorn-fritters." For this purpose the molds are rectangular in either section, this being found most suitable for the substance in question. The molds may be formed in numerous shapes and work with equal efficiency. Moreover, the compression-wheels may impress an imprint of a name, trade-mark, or such like on the contents of the mold while passing between the same.

The object of my invention is to provide an efficient, durable, and rapid continuous molding-machine, all parts easy of access and simple in construction, positive in action, and applicable for forming numerous substances into a variety of designs with uniformity of shape and size.

To such ends my invention consists in the construction and combination of parts hereinafter particularly described and claimed, reference being had to the accompanying drawings, which form part thereof, in which similar figures of reference refer to like parts throughout.

Figure 1 is a view in perspective of my improved continuous molding-machine. Fig. 2

is a detail view of a portion of the machine in partial longitudinal section in which the compression-wheels and discharging-wheel, 55 with a portion of the endless chain of molds, are clearly shown; and Fig. 3 is a detail view in perspective of a portion of the endless chain of molds in which the manner of connecting the molds is shown.

To support the mechanism and give rigidity to the machine, a suitable frame is employed, consisting of a stout horizontal bed 1, supported on legs 2, preferably four in number, secured to the extremities of the bed 1 and 65 serving a double purpose by supporting the boxing carrying the respective spindles of the discharging-wheel 3 and idler-pulley 4.

Located slightly in advance of the center of the bed 1 and nearing the end carrying the 70 discharging-wheel 3 is a pair of gudgeons 5, secured to the upper side of the bed 1, while directly opposite and secured to the under side is a similar pair of gudgeons 6. Sliding vertically in the gudgeons 5 and 6 and operated by the adjusting-screws 7 are the adjustable bearings 8 and 9, respectively. These bearings support the respective spindles of the upper and lower compression-wheels 10 and 11, respectively, thus permitting the said 80 compression-wheels to be readily adjusted, enabling their respective addenda to be operated to any desired depth within the molds.

The addenda 12 of the compression-wheels 10 and 11 represent radial teeth or a serrated 85 periphery provided with ample clearance by undercutting and in this instance are shown secured to the periphery of the central cylindrical portion of the compression-wheels. Nevertheless they can be formed as an integral part of the latter should it be found necessary. The periphery of the addendum 12 is preferably a short arc radial with the center of the wheel. In this instance the face of the addendum 12 is rectangular in shape or 90 similar to the interior of the molds. In all cases the form of the face will resemble that of the interior of the molds in whatever design they take in as far as is permitted and allow the compression-wheels 10 and 11 to mesh 95 with the endless chain of molds 13. It is obvious that the pitch of the endless chain of molds and that of the compression-wheels and discharging-wheel are uniform throughout.

The addenda 14 of the discharging-wheel 3 although differing in form are in other respects similar—that is, in place of the face being radial it is tangential, the object of which is to facilitate the discharging of the molds without crushing or disfiguring the contents. This is accomplished by the inclination of the addendum 14, as shown in Fig. 2, whereby the face meets the contents of the mold parallel with the under side and ejects the same into the chute 15 for the purpose hereinbefore described.

For convenience in handling and to support the material to be molded in a position to be readily fed to the molds is a table 16, extending on either side and overhanging the bed 1 and having the upper surface level with the top of the molds. Traveling longitudinally through the center of the table 16 in a way formed in the bed 1 is the endless chain of molds 13. Several openings are formed in the bed 1 for the following purposes: to permit the chain of molds 13 to pass from the idler-pulley 4 to the surface of the table, the operation of the compression-wheels 10 and 11, and the operation of the discharging-wheel 3.

The direction in which the several parts rotate is clearly shown by the arrows and also that of the chain of molds.

The endless chain of molds 13 consists of a plurality of molds 13^a, secured by links 17 in a manner to permit of sufficient flexibility to operate smoothly. The links 17 are preferably set in recesses 17^a, formed in the ends of the molds 13^a, and lie flush with the upper portion of the molds.

For the purpose of operating the machine a driving-pulley 18 is employed, supported on the spindle of the discharging-wheel, as shown.

The compression-wheels 10 and 11 are in this instance actuated by the endless chain of molds. The driving of the machine may be performed vice versa, or independently of the synchronical motion imparted by the endless chain of molds. This may be accomplished by sprocket wheels and chain or a chain of gears operating from the extensions of the respective spindles.

Having described my invention, what I claim as new, and desire to secure by Letters Patent, is—

1. In a continuous molding-machine, the combination of an endless chain of molds adapted to travel longitudinally over the bed of the machine, vertically-adjustable upper and lower compression-wheels, and a dis-

charging-wheel for ejecting the contents of the molds, substantially as set forth. 60

2. In a continuous molding-machine, the combination of an endless chain of molds adapted to travel longitudinally over the bed of the machine, a vertically-adjustable compression-wheel meshing with the upper side 65 of said chain of molds, a vertically-adjustable compression-wheel meshing with the under side of said chain of molds, and a discharging-wheel for ejecting the contents of the molds, substantially as set forth. 70

3. In a continuous molding-machine, the combination of an endless chain of molds adapted to travel longitudinally over the bed of the machine, an upper compression-wheel provided with a serrated periphery and adapted 75 to mesh with said chain of molds, a lower compression-wheel provided with a serrated periphery and adapted to mesh with said chain of molds, means for vertically adjusting said compression-wheels, whereby their respective addenda can be operated to any desired depth within the molds, a discharging-wheel provided with a serrated periphery and adapted to mesh with the said chain of molds, and the faces of the addenda of said discharging-wheel tangential to the periphery, whereby the faces meet the contents of the molds parallel with the under side of the same, substantially as set forth. 80

4. In a continuous molding-machine, the combination of an endless chain of molds adapted to travel longitudinally over the bed of the machine, a table surrounding a plurality of the molds and having the upper surface level with the top of the same, an idler-pulley located below the bed from the periphery of which the chain of molds pass to the surface of the same, a discharging-wheel over which the chain of molds pass to the under side of the said bed, an upper and lower compression-wheel adapted to mesh with the chain of molds, means for vertically adjusting said compression-wheels, whereby the addenda of the serrated peripheries can be operated to any desired depth within the molds, and the 100 faces of the addenda of said discharging-wheel tangential with the periphery, whereby the faces meet the contents of the molds parallel with the under side of the same, substantially as set forth. 105

Signed at Toronto this 5th day of July, 1901.

BENJAMIN FLETCHER.
